UNITED STATES PATENT OFFICE.

WILLIAM R. KINNEAR, OF COLUMBUS, OHIO.

DESIGN FOR A CEILING PLATE OR PANEL.

SPECIFICATION forming part of **Design No. 22,968**, dated December 19, 1893.

Application filed October 6, 1893. Serial No. 487,382. Term of patent 7 years.

To all whom it may concern:

Be it known that I, WILLIAM R. KINNEAR, a citizen of the United States, residing at Columbus, in the county of Franklin and State of Ohio, have invented and produced a new and original Design for Panels or Plates for Metallic Ceilings; and I do hereby declare the following to be a full, clear, and exact description of the same, reference being had to the accompanying drawing, forming a part thereof.

The main and predominant features of my design are, to wit: the corner figures comprising a knob *a*, elongated figures *b* radiating from said knob, a scroll *c* between the elongated figures; and a series of alternating knobs *e* and figures *d* extending in right lines from the elongated figures *b*.

In the drawing referred to the letter *A* marks the body of the panel or plate ornamented at

its corners with the knob *a* and two of the elongated figures *b* emanating from knob *a* and extending at angles to each other.

c designates the scroll between the elongated figures *b* and resembling the fleur-de-lis. Continuing and extending in right lines from the elongated figures *b* is the series of alternating knobs *e* and elongated figures *d*.

What I claim, and desire to secure by Letters Patent, is—

The design for a ceiling plate or panel substantially as herein shown and described.

In testimony whereof I affix my signature in presence of two witnesses.

WILLIAM R. KINNEAR.
